Oscar R. Galter, Chicago, Ill.

Application November 17, 1949, Serial No. 6,089

Term of patent 14 years

(Cl. D44—29)

To all whom it may concern:

Be it known that I, Oscar R. Galter, a citizen of the United States of America, residing at 711 West Lake Street, Chicago, Illinois, have invented a new, original, and ornamental Design for an Opener for Bottles and Vacuum Sealed Jars, of which the following is a specification, reference being made to the accompanying drawing, forming part hereof.

Referring to the drawings, Fig. 1 is a top plan view; Fig. 2 is a side elevational view; Fig. 3 is a bottom plan view; Fig. 4 is a front end view and Fig. 5 is a rear end view of an opener for bottles and vacuum sealed jars embodying my design.

I claim:

The ornamental design for an opener for bottles and vacuum sealed jars, substantially as shown.

OSCAR R. GALTER.
